UNITED STATES PATENT OFFICE

JULIUS E. HANSEN, OF ROCHESTER, NEW YORK

TRUSS

Application filed April 5, 1927. Serial No. 181,193.

The present invention relates to trusses and an object thereof is to provide a construction in which one or more pads is supported in proper position on the rupture with the minimum amount of inconvenience to the user. Another object of the invention is to provide a construction which will follow or adapt itself to the movement of the body without causing any slipping of the 10 pad or any irritation to the body of the user. Still another object of the invention is to provide a structure which will support the abdomen about a rupture.

To these and other ends, the invention consists of certain parts and combination of parts, all of which will be hereinafter described; the novel features being pointed out in the appended claims.

In the drawings:

Fig. 1 is a plan view of a truss constructed according to this invention;

Fig. 2 shows a truss in position on a body;

Fig. 3 is a section on the line 3—3, Fig. 1;

Fig. 4 is a perspective view of one of the 25 springs removed from its pocket;

Fig. 5 is a section on the line 5—5, Fig. 4; and

Fig. 6 is a fragmentary view showing the 30 inner faces of two of the pads and the flexible connection between them forming the abdominal support.

In the illustrated embodiment of the invention, there is employed a front piece 1 made in the form of a flexible apron of a 35 shape and size to extend over the abdomen and support the muscles of the latter about a rupture, this apron having two waistband sections 2 each secured thereto at 3. The waistband sections are detachably and adjustably connected at the rear of the truss in any suitable manner as by a buckle 4. Each waistband section, in this instance, embodies two layers of sheet material sewed together at 5 by two lines of stitching which provides a pocket 6 between them. This pocket extends throughout the greater portion of a waistband section and opens at the forward end of a waistband section in rear of the front piece 1. In this instance, in 45 the pocket of each waistband section is ar-

ranged a U shaped or bowed spring bar 7, one end 7^a of which is deflected downwardly to a small extent and projects beyond the open end of the pocket. This downwardly deflected port 7^a has a longitudinally extending slot 55 and a screw 8 is passed therethrough and anchored in a pad 9 of any suitable construction after being passed through one of the layers of the waistband section. The slot provides for an adjustment of the pad. 60 The rear face of the pad may have a groove 9^c in which the end of the deflected portion is received to hold the pad against turning on the portion 7^a. By removing a screw 8 it is possible to disconnect a pad 9 and 65 then slip a spring 7 from its pocket. This arrangement is provided so that the truss may be used for a single rupture or double rupture. In this instance the pad has a sponge rubber center 9^a covered by velvet 9^b. 70 A back piece 9^c of hard rubber is glued to the rear face of the sponge rubber with an interposed metal plate 9^d in which the screw 8 is anchored.

A novel means for holding down the 75 truss, to prevent its rising on the body, comprises, in this instance, two straps 10 each of which is secured at 11 at its forward end at the center piece 1, the two straps being secured to the front piece 1 at spaced points at 80 opposite sides of a center line through the front piece. The rear ends of the straps are secured by buckles 12 to slides 13 which are movable on the waistband sections 7 and preferably engage the latter at or adjacent 85 the hips of the user.

The front piece 1 prevents the slipping of the pads, thus eliminating all bruising of the flesh at or around the rupture opening. The pads are supported so that they are free 90 from all fastenings or projections at or around the rupture openings, and, at the same time, they are permitted to work independently of each other. Each pad is held against the rupture opening with only a 95 slight pressure necessary to close the rupture opening. The use of the half circle or U shaped springs arranged in two planes at slight angles to each other and connected by a flexible front piece makes it possible to 100

provide a loose construction permitting the springs to follow the joints between the legs and the body, thus not interfering with the movement of the body or the legs. The 5 springs, when in use are by reason of their rear ends, being fastened in a higher plane than their forward ends, placed under a slight twisting strain which tends to push upward on the pads, thus giving desirable action on the rupture. The truss will hold 10 any reducible rupture and positively stay in place. It is more efficacious when adjusted to a loose fit, thus eliminating constant taking up and readjustment. Its supporting tendencies are constant regardless of the position of the wearer or the degree of exertion 15 which the wearer may undergo. It may be worn night or day with perfect comfort, and it is easy to put on or take off through the single buckle at the rear of the waistband section. The front piece acts as an abdominal 20 support and supports and strengthens the muscles about a rupture as it entirely covers the pads. The hold down straps make it possible to use the bowed springs in 25 place without pressure.

What I claim as my invention and desire to secure by Letters Patent is:

1. A truss comprising a flexible abdominal support, a relatively narrow waistband for 30 supporting the abdominal support from the waist of the user, leg straps connected with the abdominal support and also with the waistband at the rear of the user, a truss pad arranged at the inner face of the abdominal 35 support independently of the latter to be held against the rupture by said support and having the abdominal support extending beyond the edges thereof to contact with the abdomen about the rupture, and a bowed 40 resilient member supported by the waistband to extend about one side of the body of the user, having a truss pad rigidly secured to the forward end and having its rear end terminating at the back of the user and supported so as not to produce any material pressure 45 on the rupture by the pad.

2. A truss comprising a flexible abdominal support, a waistband for supporting the abdominal support from the waist of the user, leg straps connected to the abdominal support and also with the waistband, two truss pads arranged at the inner face of the abdominal support to be held against the rupture by said 50 abdominal support but independently of the support and having the abdominal support extending beyond the edges thereof to contact with the abdomen about the ruptures, and two bowed resilient members supported by 55 the supporting means of the abdominal support to extend about opposite sides of the body, each bowed member having one of the truss pads rigidly secured to the forward end 60 thereof and having its rear end terminating 65

at the back of the user and supported so as not to produce any material pressure on the rupture by the pad carried by such bowed member.
